US00D841753S

(12) **United States Design Patent** (10) **Patent No.:** **US D841,753 S**
(45) **Date of Patent:** **** Feb. 26, 2019**

(54) **FLOTATION WRIST-WEAR DEVICE**

(71) Applicant: **Athanasiros Agapiades**, Gredley, CA (US)

(72) Inventor: **Athanasiros Agapiades**, Gredley, CA (US)

(**) Term: **15 Years**

(21) Appl. No.: **29/647,009**

(22) Filed: **May 9, 2018**

(57) **CLAIM**

The ornamental design for a flotation wrist-wear device, as shown and described.

DESCRIPTION

FIG. 1 is a top, front, right side perspective view of the flotation wrist-wear device in accordance with the design; FIG. 2 is a top plan view of the flotation wrist-wear device of FIG. 1;

FIG. 3 is a bottom view of the flotation wrist-wear device of FIG. 1;

FIG. 4 is a right side lateral view of the flotation wrist-wear device of FIG. 1;

FIG. 5 is a left side lateral view of the flotation wrist-wear device of FIG. 1;

FIG. 6 is a front view of the flotation wrist-wear device of FIG. 1;

FIG. 7 is a rear view of the flotation wrist-wear device of FIG. 1; and,

FIG. 8 is a top, front, right side perspective view of the flotation wrist-wear device mounted to a wearer and showing the balloon contained therein in the deployed position. The broken lines that illustrate portions of the flotation wrist-wear device form no part of the claimed design. The broken lines showing the figure of a user (arm of a wearer) are for the purpose of illustrating environment and form no part of the claimed design.

1 Claim, 6 Drawing Sheets
